UNITED STATES PATENT OFFICE.

CHARLES D. BONSALL, OF PARNASSUS, PENNSYLVANIA, ASSIGNOR TO UNION METAL PRODUCTS COMPANY, OF CHICAGO, ILLINOIS, A CORPORATION OF DELAWARE.

CAR WALL STRUCTURE.

Application filed July 24, 1922. Serial No. 577,035.

To all whom it may concern:

Be it known that I, CHARLES D. BONSALL, residing at Parnassus, county of Westmoreland, State of Pennsylvania, and being a citizen of the United States, have invented certain new and useful Improvements in Car Wall Structures, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

My invention has for its object to provide an all metal car construction of novel character which is unusually strong for its weight and durable throughout, which may be conveniently and economically manufactured and transported, is weather proof and which possesses certain other desirable and advantageous features to be hereinafter described and claimed. My sheet metal wall structure is applicable to box, automobile, gondola, stock or any other type of railway equipment.

The ends of railway cars are subject to considerable stress due to the shifting of the lading. These blows are imparted to the end over the entire area thereof, or to local or concentrated thrust. Wheat is loaded to substantially the top of the car which causes all the blow to be imparted over the entire area of the end. Lumber is loaded to the top and upon impact the top boards shift causing a blow to be imparted at the top of the end. Sand, chats and other plastic loads and light pipe cause blows at the middle of the car, whereas rail, steel plates, castings and the like cause blows at the bottom of the car.

While, of course, efforts are made to block the lading in the car, the heavy locomotives, the emergency air brake and the classification hump break the lading away from its moorings and throw it against the end of the car.

A rigid end to a car, and particularly a large box car, materially strengthens the en-

tire superstructure to resist the torsional and weaying movements which not only rack the car to pieces, but causes leaky roofs and inoperative and leaky doors with their consequent damage claims. As it costs as much to transport a ton of freight car as it does a ton of lading it is imperative that the weight of the car must be kept as low as possible, therefore, the end must be very light as well as strong. As freight cars are frequently damaged in wrecks and by other unfair usage, any end will be damaged in service, therefore, it must be capable of being easily repaired with such meagre facilities as the railroads are equipped with at their outlying repair points.

In the drawings:

Fig. 1 shows an end elevation of a box car with my end applied thereon.

Fig. 2 shows a section on line 2—2 of Fig. 1.

Fig. 3 shows an elevation of one of the plates before it is applied to the car.

Fig. 4 shows a vertical cross section on line 4—4 of Fig. 3.

Figs. 5 and 6 show modified sections on line 4—4 of Fig. 3.

Fig. 7 shows an elevation of a modified form of the plate before it is applied to the car.

Fig. 8 is a section on the line 8—8 of Fig. 7.

Fig. 9 shows a vertical section of two metal plates secured together forming the end of a box car, said section taken along the center line of the car showing a modified form.

Fig. 10 is similar to Fig. 9 and shows another modification.

Fig. 11 is an elevation of the metal plate before it is applied to the car wherein the horizontal portions above the panels are wider than the horizontal portions below the panel.

Fig. 12 is a section on the line 12—12 of Fig. 11.

Numeral 1 is the side wall of the car, 2 the under frame, 3 the roof to which my plate metal wall structure is attached by various and any convenient means. Numerals 4, 5 and 6 are top, middle and bottom sheets respectively of a car end wall made in three pieces. However, the end may be made in a single sheet or any num-

ber of sheets and still fall within the scope of my invention. Numeral 7 is the side walls of a rectangular panel pressed from the main portion of the plate. Numeral 8 5 is the side walls of a rectangular panel pressed from the elevated portion of the first mentioned panel and numeral 9 is the side walls of a rectangular panel pressed from the elevated portion of the last mentioned panel. Margins 10, 11 and 12 are then formed between panel within panel.

While I have shown in Fig. 3 three panels within panels, rectangular or otherwise, my invention covers any plurality of panels 15 within panels depending upon conditions to be met by the designer.

In order to conserve horizontal space it may be advisable to reverse the direction of some of the panels without diminishing the 20 strength of the panel an as entirety. Suggestions along this line are shown in Figs. 5 and 6. Panels of different depths are thus obtained. The deeper panels, such as shown in Figs. 6 and 8, have greater strength than 25 the shallower panels when acting as beams.

Fig. 2 shows the end wall comprising three duplicate plates and further shows nailing strips 16 secured to the sheet by bolts 17 to which the lining boards are nailed. 30 The end lining 18 is to prevent moisture due to condensation coming in contact with the lading and also to provide nailing surfaces to which the lading may be anchored. This lining 18 is not a part of my invention except a combination claim I make for means 35 of securing the lining to the end wall which is peculiar to my particular end wall.

Experience has shown that the lower portion of car end walls are subjected to greater 40 and more frequent end thrust than any other part thereof, therefore, it is essential that the lower part adjacent the floor be stronger than any other part.

To obtain this desired result I make the 45 lower plate 19 narrower than the upper plate 20 but each plate may have the same number of panels within panels, as shown in Fig. 9. It is obvious that the lower plate 19 is then stronger per linear vertical inch than the upper plate.

The desired result described in the last 50 paragraph may be obtained, as shown in Fig. 10, wherein the lower plate 21 is narrower than the upper plate 22 but the margins 23 between the panels are all the same width, thus requiring a greater number of panels within panels in the upper sheet than in the lower sheet. These panels in the upper sheet 22 may be shallower than the panels 60 in the lower sheet 21.

Another method of obtaining a sheet metal wall structure which is stronger adjacent the floor than near its top is to position the panels within the panels near the bottom of the plate, as shown in Figs. 11

and 12. There are then more horizontal walls between the panels near the floor to resist shifting loads. It may be advisable when designing an end for a box car to use the bottom sheet, as shown in Figs. 11 and 70 12, and use the upper sheets, as shown in Figs. 1 and 2, or the uppermost plate may be flat.

What I claim is:

1. A sheet metal structure for car walls 75 having a panel embossed within a panel, said panels projecting in the same direction.

2. A sheet metal structure for car walls having a rectangular panel embossed within a rectangular panel, said panels projecting 80 in the same direction.

3. A sheet metal structure for car walls having an embossed panel pressed from the plane of the sheet, with flat margins surrounding said panel, and an embossed panel 85 pressed from the first mentioned panel with flat margins surrounding the last mentioned panel.

4. A sheet metal structure for car walls having an embossed panel pressed from the plane of the sheet with flat margins surrounding said panel and an embossed panel 90 pressed from the first mentioned panel with flat margins surrounding the last mentioned panel, the margins at the sides of the panels 95 being wider than the margins at the ends of the panels

5. A sheet metal wall structure for railway box cars, having a plurality of metal 100 sheets connected along a horizontal line, said metal sheets having an embossed panel forming an elevated flat surface with flat margins surrounding said panel, and an embossed panel formed in said flat surface forming another elevated flat surface, the horizontal 105 flat margins of the upper metal sheet being wider than the horizontal flat margins of the lower metal sheet.

6. A sheet metal wall structure for railway box cars, having a plurality of metal 110 sheets connected along a horizontal line, each metal sheet having an embossed panel forming an elevated flat surface with flat margins surrounding said panel, and an embossed panel formed in said flat surface 115 forming another elevated flat surface.

7. A sheet metal wall structure for railway box cars, having a plurality of metal sheets connected along a horizontal line, each metal sheet having an embossed panel 120 forming an elevated flat surface with flat margins surrounding said panel, and an embossed panel formed in said flat surface forming another elevated flat surface, the panels in the lower sheet being deeper than the panels in the upper sheet.

8. A sheet metal wall structure for railway box cars, having a plurality of metal sheets connected along a horizontal line, each metal sheet having an embossed panel 130

- forming an elevated flat surface with flat margins surrounding said panel, and an embossed panel formed in said flat surface forming another elevated flat surface, the 5 horizontal flat margins of the upper metal sheet being wider than the horizontal flat margins of the lower metal plate, the embossments in the lower sheet being deeper than the embossments in the upper sheet.
- 10 9. A sheet metal wall structure for railway cars comprising a plurality of metallic sheets connected along horizontal lines, each sheet being formed with a series of panels within panels.
- 15 10. A sheet metal wall structure for railway cars comprising a plurality of metallic sheets connected along horizontal lines, each sheet being formed with a series of panels within panels, the panels in the lower sheet 20 being deeper than the panels in the upper sheet.
11. A sheet metal structure for car walls having an embossed panel pressed from the plane of the sheet, with flat margins surrounding said panel, and an embossed panel 25 pressed from the first mentioned panel with flat margins surrounding the last mentioned panel, said embossed panels projecting in the same direction.
- 30 12. A sheet metal structure for car walls having a rectangular embossed panel pressed from the plane of the sheet, with flat margins surrounding said panel, and a rectangular embossed panel pressed from 35 the first mentioned panel with flat margins surrounding the last mentioned panel, said embossed panels projecting in the same direction.
- 35 13. A sheet metal structure for car walls having an embossed panel pressed from the plane of the sheet, with flat margins surrounding said panel, and an embossed panel 40 pressed from the first mentioned panel with flat margins surrounding the last mentioned panel, said embossed panels projecting in opposite directions.
- 45 14. A sheet metal structure for car walls having a rectangular embossed panel pressed from the plane of the sheet, with flat margins 50 surrounding said panel, and a rectangular embossed panel pressed from the first mentioned panel with flat margins surrounding the last mentioned panel, said embossed panels projecting in opposite directions.
- 55 15. A sheet metal structure for car walls having an embossed panel pressed from the plane of the sheet, with flat margins surrounding said panel, and an embossed panel 60 pressed from the first mentioned panel with flat margins surrounding the last mentioned panel, said embossed panels projecting in opposite directions, and one of said embossed panels being deeper than another embossed panel.
16. A sheet metal structure for car walls having an embossed panel pressed from the plane of the sheet with flat margins surrounding said panel, and an embossed panel 70 pressed from the first mentioned panel with flat margins surrounding the last mentioned panel, the margins on one side of said panels being narrower than the margins on the other side of said panels.
17. A sheet metal wall structure for railway cars having a plurality of metal sheets connected along a horizontal line, each sheet having an embossed panel forming an elevated flat surface with flat margins surrounding said panel, and an embossed panel 75 80 formed in said flat surface forming another elevated flat surface, the margins at the sides of an embossed panel in an upper sheet being wider than the margins at the sides of an embossed panel in a lower sheet.
18. A sheet metal wall structure for railway cars having a plurality of metal sheets connected along a horizontal line, each sheet having an embossed panel forming an elevated flat surface with flat margins surrounding said panel, and an embossed panel 85 90 formed in said flat surface forming another elevated flat surface, the margins at the sides of an embossed panel in an upper sheet being wider than the margins at the sides of an embossed panel in a lower sheet, the panels in the lower sheet being deeper than the panels in the upper sheet.
19. A sheet metal structure for car walls having an embossed panel pressed from the plane of the sheet, with flat margins surrounding said panel, and an embossed panel 95 100 pressed from the first mentioned panel with flat margins surrounding the last mentioned panel, one of said embossed panels being deeper than the other said embossed panel.
20. A sheet metal structure for car walls having a panel embossed within a panel so as to form margins at the sides and ends of said panels, the margins at the sides of one 105 110 of said panels being wider than the margins at the ends of that panel.
21. A sheet metal structure for car walls having a panel embossed within a panel so as to form margins at the sides and ends of said panels, the margin on one side of one of said panels being narrower than the margin on the other side of that panel.
22. A sheet metal wall structure for railway cars having an upper and lower sheet 115 120 connected along a horizontal line, each sheet having an embossed panel pressed from the plane of the sheet with flat margins surrounding said panel, and an embossed panel pressed from the first mentioned panel with flat margins surrounding the last mentioned panel, the lower sheet having a greater 125 number of panels than the upper sheet.
23. A sheet metal structure for car walls having an embossed panel pressed from the 130

4

plane of the sheet, with flat margins surrounding said panel, and an embossed panel pressed from the first mentioned panel with flat margins surrounding the last mentioned panel, the margin on one side of one of said panels being narrower than the margin on the other side of that panel.

5 24. A sheet metal structure for railway cars having an upper and a lower metallic sheet connected along a horizontal line, each

sheet being formed with a panel within a panel.

6 25. A sheet metal structure for railway cars having an upper and a lower metallic sheet connected along a horizontal line, each ¹⁵ sheet being formed with a panel within a panel, a panel in the lower sheet deeper than any panel in the upper sheet.

CHARLES D. BONSALL.
